PHEASANT BROODER

John B. Olson, Arnold Zenk and William M. Willett, Fort Atkinson, Wis., assignors to James Manufacturing Company, Fort Atkinson, Wis., a corporation of Wisconsin

Application October 8, 1937, Serial No. 167,880

5 Claims. (Cl. 119—33)

The present invention relates to brooders particularly adapted for baby pheasants, and has for one of its objects, providing means for conveniently preserving the necessary sanitary conditions, for caring for and feeding the babies and for moving the building from place to place.

5 A further object of the present invention is to provide a building which is particularly adapted for out-of-doors and whereby a warm, dry, draftless shelter is provided.

10 In buildings of the class, one of the difficult problems is to prevent the accumulation of droppings on the floor. In the present invention we provide a removable screen which acts as the floor for the babies and a removable pan positioned under the screen which acts to collect the droppings, the pan and screen being removable drawer-like from the exterior of the building by the attendant.

20 A further object of the present invention is to provide a simple hover having means for adjusting the device to accommodate various sized babies. The unit is considerably smaller than the floor space, thus the babies have a choice 25 between remaining under the heating unit and exercising on the floor where it is cooler.

An important object of our invention is to provide a unit heating device or hover which, in addition to being adjustable vertically may be lifted from its front lid-like, high enough to expose the entire floor space so all of the babies 30 may be seen and inspected.

It is a further object of the present invention to provide means for automatic thermal control of the heat and manual control of the ventilation and convenient access to the babies from the exterior.

To these and other useful ends our invention 40 consists of parts, combinations of parts or their equivalents as hereinafter set forth and claimed and shown in the accompanying drawings in which:

Fig. 1 is an end elevation of our improved 45 brooder building illustrating one of the hinged roof portions in its raised position.

Fig. 2 is a side elevation of the device as shown in Figure 1.

Fig. 3 is the other end elevation of the building 50 as shown in Figure 1.

Fig. 4 is a horizontal sectional view of the building taken on line 4—4 of Figure 3.

Fig. 5 is a transverse sectional view of the device shown in Figures 1, 2 and 3 and taken on 55 line 5—5 of Figure 2.

Fig. 6 is a bottom view of the hover as illustrated in Figures 4 and 5.

Fig. 7 is a transverse section of the hover as shown in Figure 5, taken on line 7—7 of Figure 6.

Fig. 8 is a detail fractional view illustrating 5 the means for opening and closing the outlet doors to the compartments.

Fig. 9 is a vertical section taken on line 9—9 of Figure 8.

Fig. 10 is a fractional section of the droppings 10 pans taken on lines 10—10 of Figure 4.

As thus illustrated in the various figures the device consists of a building which is in its entirety designated by reference character A. The heating units or hovers are designated in their 15 entirety by reference character B.

Building A comprises end walls 10 and 11 and side walls 12—12. A floor member 13 is provided having as a support at each end skid members 14—14 each being cut-away at its bottom ends 20 as at 15 to thereby provide means whereby the building may be easily transported on the surface of the ground in a manner well known to the art.

We provide gable roof members 16—16 which 25 are secured to the end members 10 and 11 in any desired manner, thus forming a gable roof which is adapted to cover the inner half of each compartment of the building. The other halves of the compartments are adapted to be covered by 30 roof members 17—17 each being hingedly secured to members 16 as at 18. Members 17 may be lifted door-like on their hinges (see Figure 1) and thus expose the entire compartment to view and whereby the attendant may reach every part 35 of the compartment from the exterior.

The building is divided into compartments by means of a partition wall 25 which extends from member 13 vertically to a point as at 26. The balance of the partition is preferably a screen 40 27. Thus, two elongated compartments 28 and 29 are formed having therebetween means for providing suitable ventilation from one compartment to the other.

In brooders of the class which are generally 45 left in the open and exposed to the elements, the roof must be waterproof and, for obvious reasons, extend a distance over the end and side walls of the building as clearly illustrated in Figures 1, 2, 3, and 5. We provide a rubber 50 fabric joint 30—30 between members 16 and 17. The upper edge of this joint is lapped under the roofing material 31 and the lower edge, over the roofing material 32, thus to make this part 55 of the roof water tight and permit the raising

and lowering of the hinged part of the roof.

In order to insulate the compartments from the exterior we provide insulating material for the inner walls and roof as follows: Narrow spaced strips 33 are provided and insulating boards 34-34 are secured to these strips as illustrated in Figures 4 and 5, thus to insulate the side walls of the building.

We provide strips 33 and insulating boards 10 36-36 on members 16 as illustrated in Figure 5 and we also provide insulating strips and boards 37-37 on members 17, thus the roof members are insulated. Strips 33 are provided on the inner sides of the end walls 10 and 11 of the building 15 to which we secure insulating boards 38. Thus it will be seen that we have provided a strong, compact, weather-proof, insulated building, the insulation consisting of the walls and roof of the building, dead air spaces clearly illustrated in 20 Figures 4 and 5 and insulating boards.

In devices of the class, sanitation is just as important as the means for weather-proofing the building. We provide means for removing the droppings and protecting the birds from 25 contact therewith as follows:

Elongated openings 40-40 in one end of the building are provided (see Figures 2 and 3) each having a door 41-41 which is hingedly mounted 30 as at 42-42. We provide strips 43-43 which act as guides between which droppings pans 44 and 45 are positioned, (see Figure 3). The strips are slightly higher than the height of the pans. Pans 44 and 45 are made one half 35 the length of the inclosure. Pan 44 is similar to pan 45 but is provided with a loop 46 which hooks over the flanged end of pan 45 as clearly illustrated in Figure 10, thus when pan 44 is removed, pan 45 will be pulled into the position formerly occupied by pan 44, then it also may 40 be removed from the inclosure and when these pans are replaced, 45 is first moved into the position of pan 44, the loop 46 is placed over the end of pan 45 as illustrated and then pan 44 is moved into its position. Thus the pans are 45 made in a convenient size for handling and means are provided for conveniently removing and replacing the pans.

We provide a frame 47 on the upper part of 50 which we secure a wire mesh screen 48. The frame is adapted to rest on members 43 and the opening 40 is high enough to permit the insertion and removal of this frame and screen assembly. The entire assembly is very light and 55 easily handled therefore it is practical to make this unit in one piece. We provide spaced rods 51, the ends being secured to the frame members close to the top thereof, thus screen 48 is provided with suitable supports to prevent sagging.

Screen 48 is made of mesh which is small enough to act as a floor for the chicks or baby pheasants but is made large enough whereby the droppings will fall into pans 44 and 45.

We provide a strip 49 which extends around 65 the wall of the compartment as clearly illustrated in Figures 4 and 5 which is secured to the walls as at 59. The lower edge extends downward and inward terminating a short distance above 70 screen 48 and far enough inward to divert any droppings into the pans; and furthermore, the chicks will not be able to walk on this member and therefore it to a large extent will not be contaminated.

75 It will be seen that the baby pheasants or

chicks are provided with a suitable floor to walk on which will be kept practically clear from droppings and contamination and that the screen and pans may be easily removed, cleaned and replaced either simultaneously or individually. 5

In brooders of the class it is necessary to provide means for economically heating the interior and the means provided must also act as a hover under which the babies may gather and secure the benefit of a temperature which is high 10 enough to insure their comfort. At the same time, the hover must be smaller than the compartment so that the babies may have exercise room where it is cooler. Very young babies will 15 remain largely under the hover but as they grow 15 and have more strength they will seek a cooler temperature and when necessary, they will go back to the hover for warmth. Therefore we provide hover B having a relative size as clearly indicated in Figure 4 and a cover as indicated in 20 Figure 5.

Hover B is constructed as follows: (see Figures 6 and 7). Side and end frame members 60 and 61 are provided, the upper side of which is closed with an insulating board 62 and the lower side 25 is covered by means of a wire screen 63 and preferably black fabric cloth 63a thus to permit passage of evenly diffused heat downwardly. This screen is preferably a combination of wire 30 and cloth which is secured to the bottom of the frame members by means of strips 64 (see Figure 7). We provide a cover 65 which is shaped as illustrated in Figures 4 and 5 and is secured to the frame as illustrated. The cover has an angle 35 whereby the babies will not be able to roost thereon. We also provide a plate 66 which is loosely positioned on the point of the cover by cotter pins 67 whereby this plate may tilt in either direction. Thus the babies will not be 40 able to roost on the apex of the cover. On each end of unit B we provide bars 68-68 which extend rearwardly to a point adjacent partition 25 and have a rod 69.

We provide notched bars 70-70 each secured 45 to partition 25 as illustrated in Figures 4 and 5. The notches are tapered downwardly whereby rods 69 may rest by gravity therein.

On the free ends of units B we secure chains 71-71 which pass through enlarged openings in 50 the free ends of brackets 72. Slots are provided in the lower ends of brackets 72 whereby the chain links may find lodgement therein. Thus unit B at its hinged and free sides may be raised and lowered and held in a horizontal position as 55 indicated on the left of Figure 5.

It is frequently necessary to have access to the entire floor space of the brooder and also a full view of the entire enclosure. It will be noted on the right of Figure 5 that member B 60 may be lifted and held as indicated for this purpose.

For heating the hover we provide a resistor 75 which is held in the position illustrated in Figure 6 by porcelain insulating knobs 76, the ends as at 65 71 being secured to an insulating block 78. A wire 80 leads from block 78 preferably to a red light 79 and a wire 81 leads from block 78 to a thermally controlled switch 82. The wires then lead from members 82 and 79 to the exterior 70 through an insulating sleeve 83. These wires are then connected to a source of electrical supply either by means of a socket placed on member 65 or otherwise. The thermal switch 82 is provided with a control screw 84 by means of which the 75

temperature at which the switch will operate, may be manually adjusted.

Suitable doors provide access to the controlling member 84 and the red light bulb 79. Thus one may open this door and observe by the light whether the resister is in circuit or not and also make necessary temperature adjustments.

In devices of the class it is necessary to provide ventilation. For this purpose we provide elongated openings 93-93 having lids or doors 94-94 which are hinged to the end wall of the building as at 85-85. We provide friction contact springs 96-96 having a suitable stop whereby doors 94 may be closed or opened or left in any desired position.

We provide outlets 89-89 from each of the compartments and doors for the same as follows:

Suitable guides 97 and 98 are provided as sliding supports for doors 99-99. Each door has a channel bracket 100 into which the operating bar 101 loosely extends. The bar is provided with a bent hand piece 102. The outer ends of members 101 are loosely supported by brackets 103. We provide a rivet 104 which extends through bracket 100 and door 99, as illustrated in Figure 9, leaving room above this rivet for the passage of bar 101; thus when the door is opened, the bar may be lifted and moved forward to the position illustrated on the right of Figure 1. The inner end of the bar is provided with a downwardly extending portion 105 and a notch for the reception of the rivet 104, whereby the door may be moved in either direction when thus engaged.

While the brooder and hovers illustrated are particularly suited for brooding pheasants they may also be used for brooding baby chicks and the like, we contemplate the use of several different frames having several different sized mesh screens, thus to provide for baby pheasants, baby chicks and older birds.

In the various figures of the drawings we have illustrated our preferred form of the device. It will be understood that various detail changes may be made without departing from the spirit and scope of the invention as recited in the appended claims.

Having thus shown and described our invention we claim:

- 50 1. A device of the class described, comprising in combination an inclosure having a uniform roof, a lower portion of said roof being free and hingedly mounted to the other portion to thereby provide access to the inclosure, a floor in said inclosure, a pan slidably positioned on said floor, a screen slidably positioned above and adjacent said pan and adapted to act as a supplemental floor for the inclosure, a narrow transverse opening in one wall of said inclosure the top of said floor adjacent said opening forming the bottom of the opening and the top of said opening being above the horizontal plane of the top of said screen, said opening having a removable closure whereby the screen or pan individually may be removed drawer-like from said inclosure through said opening, a hover positioned in said inclosure being adapted to occupy a relatively small floor space, vertically positioned spaced notches secured to the rear wall of said inclosure, said hover having means spaced therefrom and adapted to engage said notches and form a hinge support for the rear side of the hover, and adjustable means on the front side of said hover whereby the hover may be adjusted hinge-like or lifted lid-like to thereby expose to view the entire surface of said supplemental floor.
- 55 2. A device of the class described, comprising in combination an inclosure having a uniform roof, a lower portion of said roof being free and hingedly mounted to the other portion to thereby provide access to the inclosure, a uniform floor in said inclosure adapted to occupy the entire space between the four walls of the inclosure, a pan slidably positioned on said floor, a screen slidably positioned above and adjacent said pan and adapted to act as a supplemental floor for the inclosure, a narrow transverse opening in one wall of said inclosure, the top of said floor adjacent said opening forming the bottom of the opening and the top of said opening being above the horizontal plane of the top of said screen, said opening having a removable closure whereby the screen or pan individually may be removed drawer-like from said inclosure through said opening, a hover positioned in said inclosure being adapted to occupy a relatively small floor space, said hover positioned a distance in front of the rear wall of said inclosure and having hinged connections thereto whereby the front of the hover may be raised lid-like to thereby expose to view said supplemental floor, and means secured to the front of said hover adapted to regulate the vertical position thereof, said hinge connection being adjustable vertically whereby said hover may be positioned at different heights.
- 60 3. A device of the class described, comprising in combination an inclosure having a uniform roof, a lower portion of said roof being free and hingedly mounted to the other portion to thereby provide access to the inclosure, a uniform floor in said inclosure adapted to occupy the entire space between the four walls of the inclosure, a pan slidably positioned on said floor, a screen slidably positioned above and adjacent said pan and adapted to act as a supplemental floor for the inclosure, a narrow transverse opening in one wall of said inclosure, the top of said floor adjacent said opening forming the bottom of the opening and the top of said opening being above the horizontal plane of the top of said screen, said opening having a removable closure whereby the screen or pan individually may be removed drawer-like from said inclosure through said opening, a hover positioned in said inclosure being adapted to occupy a relatively small floor space, said hover positioned a distance in front of the rear wall of said inclosure and having hinged connections thereto whereby the front of the hover may be raised lid-like to thereby expose to view said supplemental floor, and means secured to the front of said hover adapted to regulate the vertical position thereof, said hinge connection being adjustable vertically whereby said hover may be positioned at different heights, said hover comprising a box frame having a top cover and a bottom screen, a resister positioned between said top cover and screen, a roof positioned over said box providing a loft, a thermally controlled switch positioned within said hover and having a connection to said resister and an electric cable which extends through said hover roof and to a plug in one of the walls of said inclosure.
- 65 4. A device of the class described, comprising in combination an inclosure having a uniform roof a lower portion of which is free and hingedly mounted to the upper portion to thereby provide access to the inclosure, a hover positioned in said inclosure being adapted to occupy a relatively small floor space, the rear being positioned a distance from the rear wall of said inclosure and
- 70 5. engage said notches and form a hinge support for the rear side of the hover, and adjustable means on the front side of said hover whereby the hover may be adjusted hinge-like or lifted lid-like to thereby expose to view the entire surface of said supplemental floor.
- 75

- being hinged thereto, means for adjustably positioning the front of said hover, said hinge connection having means cooperating with said front adjusting means whereby the hover may be positioned at various distances from the floor and the hover may be lifted lid-like to thereby expose to view the entire surface of said floor, said hover comprising a box frame having a cover at its top and a screen on its bottom comprising wire netting and cloth, a roof on the top of said hover forming a loft, a resister under said cover and a thermally controlled switch in said loft, a pilot light in said loft having a connection to said switch whereby when said switch is closed, said 10 pilot light will operate, an electric cable extending from said switch through said hover roof and to a socket in one of the walls in said inclosure, and a removable lid in said roof whereby the interior of said loft may be made accessible.
- 20 5. A device of the class described, comprising in combination, an inclosure having a uniform floor and a gable roof, the lower portions of said roof being free and hingedly mounted to the upper portions to thereby provide access to the inclosure, a partition reaching from the apex of the 25 roof to the floor providing two separate compartments, the upper portion of said partition being formed of wire screen, adjustable air vents positioned in the end walls of said compartments

and on opposite sides of said partition and near the apex of said roof, pans slidably positioned on said compartment floors, screens slidably positioned above and adjacent said pans and adapted to act as supplemental floors for said compartments, a narrow transverse opening in one wall of each said compartments for the length or width thereof, the top of said floor adjacent said openings forming the bottom of the openings and the top of said openings being above the horizontal plane of the top of said screens, said openings having removable closures whereby said screens and pans may be removed drawer-like through said openings, hovers positioned in said compartments and being adapted to occupy a relatively small floor space, vertically positioned spaced rows of spaced notches secured to opposite sides of said partition, said hovers having means spaced therefrom and adapted to optionally engage certain said notches and form a hinge support for the rear side of the hovers, and adjustable means on the front side of said hovers whereby the hovers may be adjusted hinge-like or lifted lid-like to thereby expose to view the entire surface of said supplemental floors. 25
